UNITED STATES PATENT OFFICE.

WILLIAM H. ALBEE, OF MARLBORO, MASSACHUSETTS, ASSIGNOR TO B. A. CORBIN & SON COMPANY, OF MARLBORO, MASSACHUSETTS, A CORPORATION OF MASSACHUSETTS.

CUTTING MACHINE.

Application filed February 5, 1923. Serial No. 616,896.

This invention relates to machine for cutting blanks from sheet material and more particularly to the production by a dieing-out process of box toe blanks for boots and 5 shoes. Such blanks usually have an approximately semi-circular shape and they are cut out of sheet material having suitable characteristics for stiffening the toe portion of a shoe. 10 Because of their peculiar shape it is difficult to cut out these blanks without a considerable waste of stock. Furthermore, the cutting or "dinking" operation is relatively slow. The present invention is especially 15 concerned with these conditions and it has for its general object to expedite the cutting operation and to economize material. It is contemplated that the cutting operation can be performed most economically 20 in a rotary machine, but the handling of the waste presents peculiar difficulties in a machine of this type especially where economy of material is also an important consideration. Accordingly, the present invention 25 aims to devise a machine having a rotary die cutting roll in which the cutting elements shall be so arranged with reference to each other as to cut a maximum number of blanks from a given area of sheet material, while at the same time preventing the 30 waste material from interfering with the continuous operation of the machine. The various features of the invention will be readily understood from the following description of the preferred embodiment thereof 35 illustrated in the accompanying drawings, and the novel features will be particularly pointed out in the appended claims. In the drawings:—

40 Figure 1 is a front elevational view of the machine; Fig. 2 is a plan view; Fig. 3 is an end elevational view, at the right of the machine; Fig. 4 is a view, in longitudinal cross-section, through the cutting-die roll showing the bed roll in full below it; Fig. 45 5 is a detail view, in transverse cross-section, through the cutting-die roll and feed rolls; and Fig. 6 is a layout of the expanded cylindrical surface of the cutting-die roll 50 and the cutting dies shaped to produce box toe blanks.

In the embodiment of the invention illustrated in the drawings the main elements of the machine comprise two side frames 10 and 12; a smooth, frictionally driven bed

roll 14 journaled for free rotative movement in said side frames; a hollow cutting-die roll 16 above the bed roll journaled in boxes 18 and 20 adjustably and removably held on said side frames; a pair of feed rolls 60 22 and 24 in advance of the bed and cutting-die rolls; a waste material ejector 68 arranged within the cutting-die roll; and suitable trains of gearing from a driving shaft 26 for driving the cutting-die and feed rolls 65 at the same surface speed.

The cutting-die roll comprises a hollow cylinder 28 (Fig. 4) having ends 30 and 32 of reduced diameter which turn in the journal boxes 18 and 20. Each of these boxes can 70 slide vertically in a way formed in an upwardly projecting portion of its respective side frame and each rests upon compression springs 33 at the bottom of the way. The upper end of each way is closed by a horizontal bearing cap 34, bolted to the frame, having an adjusting screw 35 threaded therethrough for engaging the journal box beneath it. The cutting die itself comprises a second hollow cylinder, or sleeve, 36 provided with 75 cutting blades 38 on its outer surface having the desired configuration for the blank to be produced. This sleeve is slipped on the base cylinder 28 with a tight fit, abutting at one end against a shoulder 39 just inside the journal box 18, and at its other end against the journal box 20. With this construction the cutting-die roll may be set down, against the pressure of the springs 33, until just the desired clearance with the bed 80 roll is obtained. In practice it will just touch.

The cutting-die roll is driven through a gear 40 fast to the base cylinder 28 outside the journal box 18. This gear meshes with 85 a small pinion 41, journaled in an auxiliary bracket 42 pivotally mounted on the driving shaft 26 (Fig. 3), which supports also a concentric intermediate gear 43 meshing with a pinion 44 on the driving shaft. The driving shaft is journaled on the side frames (Fig. 1) and is provided with a belt pulley 45 at one end, loose on the shaft, but clutched thereto through any convenient form of clutch, indicated at 46, operated by a handle 47 (Fig. 1) pivotally mounted on a bracket 48 extending from the side frame 10. 100

The lower feed roll 24 is mounted yielding, in the customary manner on a spring seat 49 (Fig. 3), while the upper feed roll 110

22 is journaled in fixed bearings in the side frames. The two rolls are driven from a gear 50 on the cutting-die roll outside the journal box 20. This gear meshes with an intermediate pinion 51, journaled in an auxiliary bracket 52 pivotally mounted on the upper driving roll shaft, which pinion meshes with a gear 53 on said upper driving roll. The lower driving roll is rotated by the gear 53 intermeshing with a gear 54 on its shaft. The purpose of the two swinging auxiliary brackets will presently be made clear. The gearing is designed to drive the feed rolls and cutting-die roll at the same 15 surface speed.

In Fig. 6 there is shown a layout on the expanded surface of the cutting-die sleeve 36 for producing box toe blanks. It will be observed that the roll includes a circumferential series of pairs of dies, the individual dies of each pair being located side by side but in reversed relationship to each other. The metal of the sleeve, within the outline of each blank is routed out to the desired depth 25 leaving beveled, or oblique walls 55 (Figs. 4 and 5) at the inner sides of all the cutting blades 38 thus formed. The generally triangular spaces at each end of the sleeve 36, outside the irregularly shaped dies 20 formed by the blades 38, are routed out to the same depth but the outer walls 56 (Fig. 4) of the blades 38 are perpendicular to the roll surface permitting a sharp edge to be maintained. The irregularly shaped spaces 30 shown on Fig. 6 between the dies formed by the blades 38 are cut radially entirely through the metal of the sleeve 36, as shown at 58 in Figs. 4 and 5. The base roll 28 has cut through its wall an equal number 40 of holes 60 like the holes 58 in the sleeve, and in such position that the two sets, or series, register with each other when the sleeve is in place on the base roll 28 (see Fig. 4). The purpose of these registering 45 holes is to conduct the waste material to the interior of the cutting-die roll and in order to aid such discharge they are made larger at their inner ends than at their outer ends. The waste from the margins of the 50 sheet of material being cut can readily be segregated after the blanks have been cut, since it is not held tightly to the cutting-die roll. The waste material from the central portion of the sheet, however, is held tightly 55 to the cutting-die roll by reason of its being completely circumscribed by the cutting blades 38 and is found to be difficult to eject from the machine except in substantially the manner now to be described.

60 When the holes 58 and 60 have become substantially filled, the central waste pieces will begin to drop into the hollow interior of the base roll 28. Extending within the roll 28, and axially thereof, is a rod 62 (Fig. 4) resting loosely at one end in a cap 63 set

within the driving end of the roll, and held tightly at its other end in a support 64 vertically adjustable on a bracket 66 extending from the side frame 12. The rod 62, therefore, remains stationary while the cutting-die roll rotates around it. The rod carries, or has formed thereon, a helical blade 68 which extends the length of the cutting-die roll and for a short distance beyond its open end. The waste material is caught between the convolutions of the helical blade which forms a track along which the pieces are forced positively by the rotation of the cutting-die roll and the continual entry of new pieces. A suitable receptacle may be set 80 beneath the exposed end of the helical track to receive the waste pieces as they drop therefrom.

The machine is bolted to a supporting column 70 (Fig. 2) and may conveniently be 85 provided with a feed table 71 (Fig. 5), on a level with the bite of the feed rolls, and with a chute, or apron, 72 for directing the blanks to a barrel or other container. The beveled inner walls 55 of the blades 38 cause the cut 90 blanks generally to drop freely on the apron 72 but in some instances they, or the marginal waste, will stick at some point and be carried upward above the apron. To dislodge such pieces a scraper 73 depends vertically from, and is adjustably secured to (see Figs. 1, 3 and 5), a cross tie 74 screwed to the bearing caps 34. The lower edge of the scraper just clears the blades 38 and will 95 pick out any pieces partially held by the cutting-die roll and throw them down upon the apron.

In laying out different sized blanks upon the surface of the sleeve 36 of the cutting-die roll it will be necessary to vary the angle of 105 the pairs, as shown in Fig. 6, and also the diameter of the roll, making both the angle and the diameter greater or less as the size of the blank is greater or less. It is for this reason that the cutting-die roll is mounted 110 for removal. In order to remove and replace the cutting-die roll the tie rod 74 with its scraper is removed and then, on loosening the tie cap bolts and backing up the adjusting screws 35, the tie caps may be swung 115 aside, permitting the cutting-die with its bearings and gears to be lifted bodily from the frame when the gearing is disengaged. It will be recognized that with each different diameter of the cutting-die roll a variation 120 in the pitch of the gear 50 will have to be made in order to maintain the equal surface speed of the cutting-die roll and feed rolls. The purpose of the adjustable auxiliary brackets 42 and 52 will now be understood. They provide for disengagement of the gears and for a re-setting thereof when a different sized cutting-die roll is introduced. On 125 loosening the nut 75 (Fig. 3) in the frame the bracket 52 may be swung outward and 130

then adjusted to mesh the intermediate gear 51 with the new gear 50. A change in the diameter of the cutting die roll will also require an adjustment of the intermediate gear 41 to mesh with the new position of the driving gear 40. This is accomplished by swinging the auxiliary bracket 42 in the proper direction, the nut 76 having previously been loosened. The nut 76 is on the end of a tie rod 77 connecting the two side frames. The end of another tie rod is seen at 78 in Fig. 3. Since the feed track for ejecting the waste pieces must be maintained in axial alignment with the cutting-die roll, the vertical adjustment at 80 between the support 64 and bracket 66 is provided.

It will be observed that the layout of such irregularly shaped dies as the box toe blanks, as shown in Fig. 6, provides for the most economical use of the material. The diagonal arrangement in reverse pairs forming two columns, or bands, circumferentially of the cutting-die roll with intermeshing inner angles, or corners, requires a minimum width of material, and by laying the outer edges of the blanks substantially parallel to the marginal edges of the material the marginal waste is also reduced to a minimum. With right and left box toe blanks the inside angles, which are the greater angles, would be placed at the margins of the sheet material and in such case the parallel relation of the outer edges of said angles to the edge of the sheet would be more pronounced than as shown in Fig. 6. An indication of the arrangement of the dies for right and left blanks is given by the cutting-die rolls shown in Fig. 1.

The scope of the invention having been indicated and the preferred form thereof having been specifically described, what is claimed as new, is:

1. A machine for cutting blanks having, in combination, a bed roll, a cutting-die roll cooperating with said bed roll and comprising a hollow cylinder having a plurality of adjoining dies on its circumferential surface so arranged that spaces producing waste material are interspersed between said dies, said die roll having openings from said waste material spaces to the interior thereof, and means for rotating said die roll.

2. A machine for cutting blanks having, in combination, a bed roll, a cutting-die roll cooperating with said bed roll and comprising a hollow cylinder having a plurality of adjoining dies on its circumferential surface so arranged that spaces producing waste material are interspersed between said dies, said die roll having openings from said waste material spaces to the interior thereof, means for rotating said die roll, and means within said die roll for removing waste entering therein through said openings.

3. A machine for cutting blanks having,

in combination, a bed roll, a cutting-die roll cooperating with said bed roll and comprising a hollow cylinder having a plurality of adjoining dies on its circumferential surface so arranged that spaces producing waste material are interspersed between said dies, said die roll having openings from said waste material spaces to the interior thereof, means for rotating said die roll, and means within said die roll for causing waste entering therein to be ejected from an open end thereof.

4. A machine for cutting blanks having, in combination, a bed roll, a cutting-die roll cooperating with said bed roll and comprising a hollow cylinder having a plurality of adjoining dies on its circumferential surface so arranged that spaces producing waste material are interspersed between said dies, said die roll having openings from said waste material spaces to the interior thereof, means for rotating said die roll, and means within said die roll, having a fixed relation thereto, constructed and arranged to positively advance the waste material entering the roll toward an open end thereof.

5. A machine for cutting blanks having, in combination, a bed roll, a cutting-die roll cooperating with said bed roll and comprising a hollow cylinder having a plurality of adjoining dies on its circumferential surface so arranged that spaces producing waste material are interspersed between said dies, said die roll having openings from said waste material spaces to the interior thereof, means for rotating said die roll, and means co-operating with the rotating die roll to positively advance the waste material entering therein axially of the roll and out of an open end thereof.

6. A machine for cutting blanks having, in combination, a bed roll, a cutting-die roll cooperating with said bed roll and comprising a hollow cylinder having a plurality of adjoining dies on its circumferential surface so arranged that spaces producing waste material are interspersed between said dies, said die roll having openings from said waste material spaces to the interior thereof, means for rotating said die roll, and an axially arranged helical feed track entering one open end of the die roll along which the waste, introduced to the interior of the roll, is fed by the rotation of the roll.

7. A machine for cutting blanks having, in combination, a bed roll, a cutting-die roll cooperating with said bed roll and comprising a hollow cylinder having a plurality of adjoining dies on its circumferential surface so arranged that spaces producing waste material are interspersed between said dies, said die roll having openings from said waste material spaces to the interior thereof, means for rotating said die roll, and a helical track within said die roll supported at one end

in a fixed bearing formed in the roll and adjustably supported at the other end.

8. A machine for cutting blanks having, in combination, a bed roll, a cutting-die roll 5 cooperating with said bed roll and comprising a hollow cylinder having dies on its surface so arranged that waste producing spaces are interspersed between the dies and constructed to permit the waste material to 10 pass to its interior, means for supporting said roll permitting an interchange of cutting-die rolls having different diameters, and means arranged axially of said roll to eject the waste material from its interior and adjustable to retain its axial position regardless of the diameter of the cutting-die roll 15 used.
9. A cutting-die roll for blank cutting machines comprising a hollow cylinder, and a sleeve mounted thereon provided with a plurality of cutting-dies on its outer surface so arranged that spaces producing waste material are interspersed between said dies, said sleeve having openings therethrough communicating with said spaces and said cylinder having openings through its wall registering with said openings in the sleeve. 20

10. A machine for cutting blanks having, in combination, a bed roll, a cutting-die roll 25

cooperating with said bed roll and comprising a hollow cylinder, a rod extending axially within said die roll, means to rotate said die roll, a bearing block within one end of the die roll for loosely supporting one end of the rod, a bearing on the frame for clamping the other end of the rod, and a helical feed track carried by the rod. 30

11. A cutting-die roll for a box toe cutting machine, said roll having a plurality of adjoining dies on its periphery so arranged 35 that spaces producing waste material are located between said dies, said roll being provided with openings leading from said waste material spaces to the interior thereof through which the waste material may be 40 discharged.

12. A cutting-die roll for a box toe cutting machine, said roll having on the periphery thereof a circumferential series of pairs of dies with the individual dies of each pair 45 located side by side but positioned in reverse relationship to each other, whereby waste material spaces are formed between the dies, said roll having openings permitting the discharge of the waste material from said 50 spaces into the interior of the roll.

WILLIAM H. ALBEE.
